ACTUATOR CAP FOR A PRESSURIZED CONTAINER

Stanley T. Mandeltort, Highland Park, Ill., assignor to
VCA Corporation, Greenwich, Conn.

Filed Apr. 25, 1973, Ser. No. 354,345

Term of patent 14 years

Int. Cl. D9—07
U.S. Cl. D9—258

Fig. 1

Fig. 2

Fig. 4

Fig. 3

Fig. 5

FIG. 1 is a right side elevational view of an actuator cap for a pressurized container showing my new design;
FIG. 2 is a front elevational view;
FIG. 3 is a rear elevational view;
FIG. 4 is a top plan view; and
FIG. 5 is a bottom plan view.
I claim:

The ornamental design for an actuator cap for a pressurized container, as shown and described.
